UNITED STATES PATENT OFFICE.

WINFRED T. POWELL, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed November 8, 1915, Serial No. 60,271. Renewed December 19, 1921. Serial No. 523,583.

To all whom it may concern:

Be it known that I, WINFRED T. POWELL, a citizen of the United States of America, and a resident of Chicago, Cook County, Illinois, have invented certain new and useful Improvements in Automatic Telephone Systems, of which the following is a specification.

This invention relates to improvements in automatic telephone systems and more particularly to improvements in the automatic switches used in such systems.

In automatic telephone systems where the impulse sending device is capable of transmitting ten successive impulses at the most, it is customary to provide numerical switching mechanism capable of responding to not more than ten successive impulses, by providing a shaft with ten notches carrying 20 wipers adapted to engage one of ten bank levels, each level being provided with ten terminals. It is obvious that in such a system each selecting or connecting mechanism is limited to connect with any one of one hundred terminals. It is an object of this invention to provide an automatic switch capable of selecting more than the customary one hundred terminals. By this arrangement it is thus possible to increase the capacity of an exchange without increasing the number of switches.

A further object of this invention is the provision of an automatic selecting switch which is very positive and efficient in its operation.

To the foregoing and other useful ends this invention consists of matters herein-after set forth and claimed.

The features of this invention will be more clearly understood by reference to the accompanying drawings, in which Fig. 1 represents a diagrammatic illustration of the switching features, whereby one of two sets of shaft wipers may be used.

Figs. 2 and 3 taken together represent a complete connection in an automatic telephone system embodying the principles of this invention.

In Fig. 4 are shown the essential parts of a connector switch similar to that shown in Fig. 3 to which my invention has also been applied.

The automatic substation A (Fig. 2) comprises the usual receiver 4, transmitter 5, ringer 6 and condenser 7. It is also provided with a suitable impulse-sending mechanism for controlling the automatic switches, which mechanism is represented by a pair of impulse springs 8 and an impulse wheel 9, which latter may be controlled by a finger hole dial (not shown) in such a way that the impulse springs may be momentarily separated a number of times corresponding to the respective digits of the called number. This impulse-sending mechanism may be similar to that shown in United States Letters Patent to J. G. Blessing No. 1,119,394 granted Dec. 1, 1914.

The subscriber's individual switch C (Fig. 2) is of the general type of subscriber's switch shown in British patent to T. G. Martin No. 1419 of 1910, being, however of the particular type disclosed in United States Letters Patent to F. Newforth, Jr. No. 13,901 reissued Apr. 13, 1915.

The master switch D is of the same general type as that disclosed in British patent to R. W. James No. 26,301 of 1906, being however of the particular type disclosed in British patent to T. G. Martin No. 1419 of 1910, referred to previously. The function of the master switch, as is well known, is to maintain the plungers of all the idle individual switches in position to engage the terminals of an idle trunk line.

The selector switch E (Fig. 2) is of the general type of selector switch disclosed in United States Letters Patent No. 815,321 granted March 13, 1906 to Keith, Erickson and Erickson, except that the side switch is dispensed with and the circuits are modified to adapt them to operate in a system in which the central office apparatus is controlled by impulses delivered over the two sides of the line in series, as shown in British patent to T. G. Martin No. 10,376 of 1912, and is further modified to operate in accordance with the principles of my invention.

Among other details the selector E comprises a bank of contacts arranged in horizontal rows or levels, which contacts are adapted to be engaged by two sets of wipers 10, 11, 12 and 13, 14, 15 carried upon a shaft (not shown) which has a vertical and ro-

tary movement controlled by the vertical and rotary magnets 16 and 17. The operation of the switch is controlled through the medium of the line relay 18 which in turn 5 controls the vertical and rotary magnets. When rotated onto the bank terminals, all of the wipers engage corresponding contacts. However, one set of wipers is connected with the extending circuits while 10 the other set is disconnected therefrom. The switching from one set of wipers to the other is controlled by the relay 19, which relay, when in normal position, permits the line conductors and release trunk conductor to 15 be connected to the wipers 10, 11 and 12. When said relay 19 is energized the said conductors are then connected to the wipers 13, 14 and 15. The energizing circuit of relay 19 is adapted to be closed by the switch 20 shaft carrying the arm 20, which arm closes the normal springs 21 while the switch shaft is being raised for the last or tenth step. The relay 19 will lock, upon energizing, and switch the extending circuits to the other 25 set of wipers. At the same time that relay 19 is operated the switch shaft is restored to its normal position, so that the switch in responding to a second digit of the called number will raise the shaft wipers to a position 30 opposite a level of bank contacts corresponding to said digit after which they may be rotated to select an idle trunk line. The release of the switch is controlled by the release magnet 22, which upon energizing, 35 withdraws the retaining double-dog from the switch shaft. This selector is also provided with a pair of slow acting relays 23 and 24—that is relays which are slow to release their armatures after their energizing circuits are broken—a locking relay 40 25 and a switching relay 26. The controlling circuits and operation of the magnets will be more clearly set forth when the operation of the switch is described.

45 The connector switch H (Fig. 3) is of the same general type of connector switch disclosed in United States Letters Patent No. 815,176 granted March 13, 1906 to Keith, Erickson and Erickson, the circuits, 50 however, being modified to adapt the switch to operate in a system in which the central office apparatus is controlled by impulses delivered over the two sides of the line in series, as shown in British patent to T. G. Martin, No. 1419 of 1910. Among other 55 details the connector comprises a bank of contacts arranged in horizontal levels, which contacts are adapted to be engaged by a set of wipers 27, 28, and 29 carried upon 60 a shaft (not shown) which has a vertical and rotary movement controlled by the vertical and rotary magnets 30 and 31. The different operations of the switch are controlled 65 through the medium of the line relay 32. The usual back bridge relay 33 is provided

through which the called subscriber is supplied with current for talking purposes. The release relay 34 and private control relay 35 are slow acting. The magnet 36 is the usual release magnet, while 37 is the 70 busy relay and 38 is the ring cut-off relay. The private magnet 39 controls the usual side switch wipers 40, 41, 42 and 43. The relay 44 is adapted to supply ringing current from the generator R to the called line 75 for signalling purposes. The connector switch shaft (not shown) carries the arm 45, which when said shaft leaves its lowest or normal position, permits the pairs of off-normal springs 46 and 47 to close contact. Busy signalling current is furnished in the usual manner from the busy signalling machine Q.

The line switch J and all the subscriber's 80 station K are similar in all respects to the line switch C and subscriber's station A.

A general description of the apparatus involved having been given, it will now be explained how a connection can be established between the line of a calling substation A and a called substation J.

Since the apparatus herein disclosed is in general well known in the art, and is described in the publications herein referred to, its operation will be explained in a more 90 or less general manner.

When the subscriber at substation A removes his receiver preparatory to making a call, an energizing circuit is closed for the line relay 48 of the line switch C. The relay 48 upon energizing closes a circuit for the pull-in winding 49 which operates to thrust the plunger (not shown) on the end of the plunger arm 50 into a bank of contacts, thereby forcing springs 51, 52, 53 and 54 into engagement with springs 55, 56, 57 and 58, thereby extending the connection to the selector E. The cut-off arm 59 is also operated to remove the line relay 48 from control of the calling substation. The relay 100 48 being slow acting maintains the circuit of pull-in winding 49 for a short time after its own circuit is broken. When the connection is thus extended to the selector E, an energizing circuit is established for the 105 line relay 18 of said selector which extends from ground G³ through the lower winding of line relay 18, springs 60 and 61, springs 58 and 54, line conductor 62, to and through substation A, return line conductor 63, 110 springs 51 and 55, springs 64 and 65 and the upper winding of the relay 18 to the battery B. The relay 18, upon energizing, closes a circuit from ground G⁴ through springs 66 and 67 and the relay 23 to the battery B. 115 The relay 23, upon energizing, closes a circuit from ground G⁵ through springs 68, 69 and 70, along release trunk conductor 71 through springs 56 and 52 to a point 72, thence over two paths, one of which extends 120

125

130

through the hold-in winding 73 of line switch C to the battery B, the other path extends along conductor 74 to the connector private bank contacts associated with the calling line. This ground potential protects the substation A against seizure as long as the receiver is removed from the switchhook. Due to the fact that relay 48 is slow acting it maintains the circuit of winding 49 until the holding ground from G⁵ is supplied over the release conductor 71 to the holding winding 73 of line switch C to maintain the plunger in its operated position.

Assuming the called number to be 220, the calling subscriber now operates his impulse-sender or calling device for the first digit 2, thereby causing the impulse springs 8 to be separated twice momentarily, each time breaking the circuit of line relay 18 of the selector E. The slow acting relay 23 does not deenergize during the momentary interruptions of its circuit by the relay 18 and therefore each time that relay 18 deenergizes an impulse is transmitted over a circuit extending from ground G⁴, through springs 66 and 75, springs 76, springs 77 and 78, relay 24 and the vertical magnet 16 to the battery B. The vertical magnet receives two impulses over this circuit and operates to raise the switch shaft and wipers two steps to a position opposite the second level of bank contacts, and at the same time the shaft controlled contact springs 79 and 80 are closed. The slow acting relay 24 energizes when the first impulse of current is transmitted through it and maintains its armature in an attracted position during the remaining impulses of the digit. In its energized position said relay 24 closes a circuit from ground G⁵ through springs 68 and 69, springs 81 and 82 and relay 25 to the battery B. The relay 25, upon energizing, closes a circuit for itself, independent of springs 81 and 82 of relay 24 which extends from ground G⁵ through springs 68, 69 and 70, release conductor 71, springs 83, springs 84 and the relay 25 to the battery B. When the relay 24 deenergizes after the last impulse is delivered to the vertical magnet, the relay 25 remains energized, and the circuit of the rotary magnet 17 is closed over a circuit that extends from ground G⁵ through springs 68 and 69, springs 81 and 85, springs 86 and the rotary magnet 17 to the battery B. The rotary magnet, upon energizing, rotates the shaft wipers one step and by opening the springs 83, disconnects ground G⁵ from relay 25 to thereby deenergize said relay, and by separating springs 87 opens the circuit of relay 26 which was short-circuited over a circuit which extends from ground G⁵ through springs 68, 69 and 70, release conductor 71, springs 83, springs 84, springs 79, springs 87, relay 26, conductor 92, release conductor 71, springs 70, 69 and 68 back to ground G⁵. As long as relay 25 is energized the switching relay 26 is thus short-circuited. When the rotary magnet moves the shaft wipers the first step it unlocks relay 25 and opens the circuit of the switching relay 26 to prevent it from energizing at this time. The relay 25, upon deenergizing, opens the circuit of the rotary magnet at springs 86. The rotary magnet 17, upon deenergizing, permits the pairs of springs 83 and 87 to close contact. If the first trunk of the second level is idle, the switching relay 26 will immediately energize and extend the connection through to the switch ahead. If, however, this trunk is busy, the private wiper 12 finds the contact with which it engages provided with a guarding ground potential, which is transmitted to the relay 25 over a circuit that extends from ground upon said guarded contact through private wiper 12, springs 88 and 89, springs 90 and 91, springs 87, springs 79 and the relay 25 to the battery B. The relay 25 energizes to close a locking circuit for itself as previously traced as well as to close the circuit of the rotary magnet. The rotary magnet will therefore again energize to rotate the shaft wipers onto the contacts of the second trunk line. If the second trunk line is also busy the private wiper 12 will find the contact with which it engages also provided with a guarding ground potential. A circuit will again be closed to the relay 25, as before, which will close the rotary magnet circuit to advance the wipers another step and again open the circuit of relay 25. The rotary magnet continues to advance the wipers step-by-step over the contacts until the non-grounded contact of an idle line is reached by the wiper 12. When an idle line has been located and the rotary magnet permits the springs under its control to engage a circuit is closed that extends from ground G⁵, through springs 68, 69 and 70, release conductor 71, conductor 92, switching relay 26, springs 87, springs 79, relay 25 to the battery B. Relay 25 does not receive sufficient current over the last circuit to operatively energize because of the comparatively high resistance of relay 26. Relay 26, upon energizing, opens the contact of springs 76 and separates springs 90, 64 and 61 from springs 91, 65 and 60 and forces them into contact with springs 93, 94 and 95 respectively, whereupon the line relay 18 is removed from the line and the line connection is extended over the heavy conductors shown through the wipers 10 and 11 to the connector H.

The line relay 32 of the connector H, thereupon becomes energized and closes the circuit of relay 34, which in turn, upon energizing completes a circuit from ground 130

G⁸ through springs 113, release conductor 114, contact 107, private wiper 12, springs 88 and 89 springs 90 and 93, thence over two paths, one of which extends along conductor 92, relay 26, springs 87, springs 79 and relay 25 to the battery B, the other path extends from spring 93, along conductor 71, springs 56 and 52 and the holding winding 73 of line switch C to the battery B. An 10 other branch extends from the point 72 of the last circuit to the private normal conductor 74 and thence to the private bank contacts of the calling line. This circuit maintains the relay 26 and the winding 73 energized, after their original energizing circuits are broken by the relay 23, which deenergizes shortly after the line relay 18 is disconnected from the line.

The calling subscriber now operates the 20 calling device for the next digit 2, whereupon the impulse springs 8 are separated twice momentarily, each time breaking the circuit of the line relay 32 of the connector H. The relay 34 of the connector being 25 slow acting does not deenergize during the momentary interruptions of its circuit by the relay 32, and consequently each time that the latter relay deenergizes, an impulse is transmitted over a circuit extending 30 from ground G⁷ through springs 115 and 116, springs 117 and 118, relay 35, vertical magnet 30 side-switch wiper 42 (in first position) to the battery B. The vertical magnet receives two impulses over this 35 circuit and operates to raise the switch shaft and wipers two steps to a position opposite the second level of bank contacts and at the same time the shaft controlled springs 46 and 47 are closed.

The relay 35 is energized by the first impulse transmitted through it and being slow 40 acting maintains its armature attracted during the succeeding impulses of the digit. In its energized position said relay 35 closes a circuit from ground G⁸ through springs 119 and 120 and the private magnet 39 to the battery B. This circuit is broken when the relay 35 deenergizes a short time after the last impulse has been delivered to the 45 vertical magnet. The breaking of this circuit causes the private magnet 39 to deenergize thus permitting the side switch to pass to second position. In reaching second position the side switch wiper 42 connects the battery to the rotary magnet 31; said battery having previously been connected to the vertical magnet 30. The subscriber now 50 operates the calling device for the last digit 0, in response to which the connector line relay 32 operates to transmit ten impulses to the rotary magnet 31, whereby the shaft wipers are rotated onto the contacts of the desired line. The circuit of the rotary magnet extends from ground G⁷ through springs 55 115 and 116, springs 117 and 118, relay 35,

springs 121, rotary magnet 31, side-switch wiper 42 (in second position) to the battery B. The relay 35 operates in response to this digit in the same manner as for the previous digit to cause the private magnet 39 to advance the side switch another step, i. e., from second to third position. By the engagement of the side switch wipers 40 and 41 with their third position contact points the connection is completed with the called line. 70 Upon the engagement of the side-switch wiper 43 with its third position contact point, a circuit is completed through the cut-off winding of the line switch J. This circuit extends from ground G⁹ through the 75 side switch wiper 43 (in third position), private wiper 28, bank contact 122 and the cut-off winding 123 to the battery B. The cut-off winding, upon energizing, operates to disconnect the line relay 124 from the 80 called line. The connection of ground G⁹ with the connector private bank contact 122 and its multiples, prevents the called line from being seized by some other connector switch. By the engagement of the side-switch wiper 42 with its third position contact point the circuit of the ringing relay 44 is closed which extends from ground G¹⁰ through the interrupter 125, ringing relay 44, springs 126 and the side-switch wiper 42 (in third position) to the battery B. The ringing relay 44 is energized intermittently, due to the interrupter 125, and operates to disconnect the called line from the calling line and to bridge the ringing current generator R across the called line to signal the 90 called subscriber. Upon the removal of the receiver, the called substation will be provided with talking current through the windings of the back bridge relay 33, which upon energizing, closes a circuit from ground G⁹ through the side switch wiper 43 (in third position) springs 127 and the relay 38 to the battery B. The relay 38 upon energizing, opens the circuit of the 95 ringing relay at springs 126 and closes a locking circuit for itself through springs 128 independent of the springs 127. The calling subscriber is provided with talking current through the windings of the line relay 32. The connections are now in talking condition and the subscribers may converse; talking current traveling over the heavy conductors. 100

Upon the completion of the conversation 105 the calling subscriber, by returning his receiver to the switch hook, opens the circuit of the connector line relay 32. The relay 32, upon deenergizing, opens the circuit of relay 34, which in turn, upon deenergizing, 110 removes the holding ground from the release trunk conductor 114, and in addition closes a circuit from ground G⁷ through springs 115 and 116, springs 117 and 129, off normal springs 46 and the release magnet 36 to the 115

battery B. The release magnet upon energizing, operates to remove the retaining double-dog from the shaft to thereby permit the side switch and shaft to be returned to their normal position. The circuit of said release magnet is opened, when the shaft reaches its lowest position. As soon as the private wiper 28 disengages bank contact 122, caused by the release of the connector, 5 the circuit of cut-off winding 123 of switch J is opened to permit the line relay 124 to be placed within control of the substation K. When the holding ground is removed from the release conductor 114, the energizing circuits of the switching relay 26 of selector E and of winding 73 are opened. The deenergization of relay 26 completes a circuit from ground G⁴ through springs 66 and 75, springs 76, springs 77 and 130, off normal 10 springs 80 and release magnet 22 to the battery B. The release magnet, upon energizing, removes the retaining double-dog to permit the shaft to restore to normal position, the circuit of the release magnet being 15 opened when the shaft reaches its lowest position. The deenergization of the winding 73 of line switch C releases the plunger arm 50 and cut-off arm 59, thus permitting the line switch C to be returned to normal. 20 The selector E is capable of responding to two digits or series of impulses from the calling device provided (in this instance) that the first digit called be 0. Suppose that the selector E is seized for a call as 25 previously explained and that the number desired is 0220. The calling subscriber then operates his calling device for the first digit 0 thereby transmitting ten impulses over the line, which ten impulses 30 would operate to raise the switch shaft, carrying the arm 20, ten steps to close the contact of springs 21, while the last impulse is being delivered. A circuit would then be closed from ground G⁴ through springs 35 66 and 75, springs 76, springs 77 and 78, springs 21, to spring 96, thence over two paths one of which extends through spring 97 and the release magnet 22 to the battery B, the other path extends through spring 40 98 and the relay 19 to the battery B. The release magnet 22, upon energizing, restores the switch shaft to normal position. The relay 19, upon energizing, forces spring 99 into contact with spring 98 and separates 45 springs 96 and 97 from spring 98 thereby closing a locking circuit for itself extending from ground G⁵ through springs 68, 69 and 70, springs 99 and 98 and the said relay 19 to the battery B. A further result of 50 the energization of relay 19 is the shifting of springs 100, 101 and 89 from their back contacts 102, 103 and 88 into engagement with their front contacts 104, 105 and 106 respectively, whereby the wipers 10, 11 and 55 12 are disconnected from the extending circuit and the wipers 13, 14 and 15 substituted in their stead. One contact in each bank level is shown in Fig. 1, in which X is the lower bank of line contacts, Y is the upper bank of line contacts, while Z contains two sets of private contacts, the upper one, such as 107, is used in conjunction with line contacts 108 and 109 when a connection is extended to a group of connectors such as H, while the lower contact 110 is 60 used with line contacts 111 and 112 when a connection is extended to a different group of connectors such as H'. It may be stated that the connectors H' and H are similar in all respects, but that they serve 65 to complete connection with different lines. 70 The calling subscriber will operate his calling device for the second digit, which may be any digit from 1 to 0, in this instance it was taken to be 2, whereby two 75 impulses would be transmitted over the line to again operate the selector E to raise its switch shaft and wipers two steps to a position opposite the second level of bank contacts after which the wipers are automatically rotated onto an idle set of contacts in said second level to extend the connection over wipers 13, 14 and 15 to an idle connector, such as H'. The operations 80 of the apparatus from this point are similar 85 to those hereinbefore described and it is not thought necessary to illustrate or describe the same. 90 It is to be understood that the location and adjustment of the springs 21 of the selector E can be such that the arm 20 will come in contact with said springs when the shaft wipers are opposite any level of bank contacts. For instance, if the shaft closes 95 said springs when the wipers are opposite the eighth level, the capacity of the switch instead of being 19 levels would be 17 levels, and so on. 100 It is thus seen that this invention contemplates a very efficient form of selector switch which has two movements in the vertical plane with the usual horizontal movement of selecting trunks. The switch shaft having the usual ten notches and being provided with two sets of wipers, one 105 set being adapted for use when one series of digits is employed while the other set is brought into use for another series of digits. In this manner the capacity of an 110 exchange may be increased without increasing the number of numerical trunk selecting switches. It is obvious to those versed in the art that this invention is directly applicable to connector switches of any well 115 known type, and as shown in Fig. 4, may be added thereto with a very little change in the circuits of the connector. In Fig. 4 only the essential parts of the connector have been illustrated and like parts are 120 numbered the same as in Fig. 3. The relay 125 130

19^a corresponds to the relay 19 of selector E, Fig. 2. The operating magnets and other parts it will be understood are the same as those of the connector in Fig. 3.

5 While the illustration and description of this invention has been confined to automatic switches of the well known type that have first, a vertical movement to select groups and a rotary movement to find a 10 line in the selected group, it will, of course, be understood, that this invention is capable of use in connection with other forms of automatic switches in which different characters of movement are employed for 15 selecting groups and lines.

What I claim as my invention is:

1. In a telephone system, a line, a pair of 20 movable contact makers for said line, a plurality of stationary contacts associated with each maker, means for advancing said makers adjacent to one of their respective associated contacts and for then releasing said makers from said advanced position and for switching said line into engagement with 25 one of said makers, as a result of said first movement of the switch, and for then operating the said last makers to extend the line therefrom.

2. In a telephone system, a line, a pair of 30 movable contact makers for said line, a plurality of stationary contacts associated with each maker, means for bodily advancing said makers adjacent to one of their respective associated contacts and for then releasing 35 said makers from said advanced position and for switching said line into engagement with one of said makers, as a result of said first movement of the switch, and for then operating the said last makers to extend the line therefrom.

3. In a telephone system, a line, a pair of 45 movable contact makers for said line, said line normally connected to one of said makers, a plurality of stationary contacts associated with each maker, means for advancing said makers adjacent to one of their respective associated contacts and for then releasing said makers from said advanced position and for switching said line into engagement with the other of said makers, as 50 a result of said first movement of the switch, and for then operating the said last makers to extend the line therefrom.

4. In a telephone system, a line, a pair of 55 movable contact makers for said line, a plurality of groups of stationary contacts associated with each maker, means for advancing said makers adjacent to one of their respective associated groups of contacts and for then releasing said makers from said advanced position and for switching said line into engagement with one of said makers, as a result of said first movement of the switch, and for then operating the said last makers to extend the line therefrom.

5. In a telephone system, a line, a pair of 70 movable contact makers for said line, said line normally connected to one of said makers, a plurality of groups of stationary contacts associated with each maker, means for advancing said makers adjacent to one of their respective associated groups of contacts and for then releasing said makers from said advanced position and for switching said line into engagement with 75 the other of said makers, as a result of said first movement of the switch, and for then operating the said last makers to extend the line therefrom.

6. In a telephone system, a line, a pair of 80 movable contact makers for said line, a plurality of stationary contacts associated with each maker, means involving an impulse sender and a magnet responsive thereto, for advancing said makers adjacent to one of their respective associated contacts, means involving a release magnet for then releasing said makers from said advanced position, and means involving a switching relay for switching said line into engagement with 85 one of said makers, as a result of said first movement of the switch, and for then operating the said last makers to extend the line 90 therefrom.

7. In a telephone system, a line, a pair of 95 movable contact makers for said line, a plurality of stationary contacts associated with each maker, a shaft for carrying said makers, means for advancing said shaft whereby the makers may be advanced adjacent to 100 one of their respective associated contacts and for then releasing the shaft for removing the makers from their advanced position and for switching said line into engagement with one of said makers, as a result of 105 said first movement of the switch, and for then operating the said last makers to extend the line therefrom.

8. In a telephone system, a line, a pair of 110 movable contact makers for said line, a plurality of stationary contacts associated with each maker, a shaft for carrying said makers, means for advancing said shaft whereby the makers may be bodily advanced adjacent to one of their respective associated contacts and for then releasing the shaft for removing the makers from their advanced position and for switching said line into engagement with one of said makers, as a result of 115 said first movement of the switch, and for then operating the said last makers to extend the line therefrom.

9. In a telephone system, a line, a pair of 120 movable contact makers for said line, said line normally connected to one of said makers, a plurality of stationary contacts associated with each maker, a shaft for carrying said makers, means for advancing said shaft whereby the makers may be advanced adjacent to one of their respective 125 contacts and for then releasing the shaft for removing the makers from their advanced position and for switching said line into engagement with one of said makers, as a result of 130 said first movement of the switch, and for then operating the said last makers to extend the line therefrom.

- associated contacts and for then releasing the shaft for removing the makers from their advanced position and for switching said line into engagement with the other of 5 said makers, as a result of said first movement of the switch, and for then operating the said last makers to extend the line therefrom.
10. In a telephone system, a line, a pair 10 of movable contact makers for said line, a plurality of groups of stationary contacts associated with each maker, a shaft for carrying said makers, means for advancing said shaft whereby the makers may be advanced adjacent to one of their respective 15 associated groups of contacts and for then releasing the shaft for removing the makers from their advanced position and for switching said line into engagement with one of 20 said makers, as a result of said first movement of the switch, and for then operating the said last makers to extend the line therefrom.
11. In a telephone system, a line, a pair 25 of movable contact makers for said line, said line normally connected to one of said makers, a plurality of groups of stationary contacts associated with each maker, a shaft for carrying said makers, means for advancing said shaft whereby the makers may be advanced adjacent to one of their respective 30 associated groups of contacts and for then releasing the shaft for removing the makers from their advanced position and for switching 35 said line into engagement with the other of said makers, as a result of said first movement of the switch, and for then operating the said last makers to extend the line therefrom.
12. In a telephone system, a line, a pair 40 of movable contact makers for said line, a plurality of stationary contacts associated with each maker, a shaft for carrying said makers, means, involving an impulse sender 45 and a magnet responsive thereto, for advancing said shaft whereby the makers may be advanced adjacent to one of their respective associated contacts, means involving a release magnet for then releasing the shaft 50 for removing the makers from their advanced position, one of said pair of movable contact makers normally connected to said line, means involving a switching relay for switching said line into engagement with 55 another of said makers, lines terminating in said stationary contacts, busy test circuits associated with said lines, and means whereby when said first means is again operated to move the makers adjacent to a group of 60 contacts the makers may be moved into engagement with one of said lines and if the line is busy the makers are advanced automatically through the instrumentality of the corresponding busy test circuit onto the next 65 contact.
13. In a telephone system, an automatic switch, a plurality of groups of lines associated with said switch, a plurality of groups of wipers for engaging said lines, said switch having means for giving said 70 wipers a plurality of numerical operations to select a group and a non-numerical operation for selecting an idle line in the selected group; means for switching a connection from one of said groups of wipers to another group. 75
14. In a telephone system, an automatic switch, a plurality of groups of lines associated with said switch, a plurality of groups of wipers for engaging said lines, 80 said switch having means for giving said wipers a plurality of numerical operations to select a group and a non-numerical operation for selecting an idle line in the selected group, means comprising a relay for switching a connection from one of said groups of wipers to another group. 85
15. In a telephone system, an automatic switch, a plurality of groups of lines associated with said switch, a plurality of groups of wipers for engaging said lines, said switch having means for giving said wipers a plurality of numerical operations to select a group and a non-numerical operation for selecting an idle line in the selected 90 group, and means for extending a connection through only one of said groups of wipers. 95
16. In a telephone system, an automatic switch, a plurality of groups of lines associated with said switch, a plurality of groups of wipers for engaging said lines, said switch having means for giving said wipers a plurality of numerical operations to select a group and a non-numerical operation for selecting an idle line in the selected 100 group, a relay, means controlled by said relay for extending a connection through only one of said groups of wipers. 105
17. In a telephone system, an automatic switch having an extending circuit, said switch having numerical and non-numerical operations, a plurality of groups of lines associated with said switch, a plurality of groups of wipers for engaging said lines, 110 one of said groups of wipers being normally connected with said extending circuit while the other set is disconnected therefrom, and means controlled by the numerical operation of said switch for disconnecting said connected group and for connecting said disconnected group. 115
18. In a telephone system, an automatic switch having an extending circuit, said switch having numerical and non-numerical operations, a plurality of groups of lines associated with said switch, a plurality of groups of wipers for engaging said lines, one of said groups of wipers being normally 120 connected with said extending circuit while 125

the other set is disconnected therefrom, and means comprising a relay controlled by the numerical operation of said switch for disconnecting said connected group and for connecting said disconnected group.

19. In a telephone system, an automatic switch, a line extending to said switch, groups of lines extending from said switch, a plurality of groups of wipers for engaging said lines, means for transmitting a series of impulses to operate said switch and to cause said switch to automatically select an idle line in one of said groups of lines and means comprising a relay in said switch for electing one of said groups of wipers, a circuit for said relay, said circuit adapted to be closed by the transmission of a predetermined number of impulses.

20. In a telephone system, an automatic switch, plurality of groups of lines terminating in said switch, a plurality of groups of wipers for said switch for engaging said lines, means for transmitting a plurality of series of impulses for operating said switch, and means responsive to an impulse of the first series for releasing said switch and for electing a group of wipers.

21. In a telephone system, an automatic switch, a plurality of groups of lines terminating in said switch, a plurality of groups of wipers for said switch for engaging said lines, means for transmitting a plurality of series of impulses for operating said switch, means in said switch responsive to an impulse of the first series for releasing said switch and for electing a group of wipers.

22. In a telephone system, an automatic switch, a plurality of groups of lines terminating in said switch, a plurality of groups of wipers for said switch for engaging said lines, means for transmitting a plurality of series of impulses for operating said switch, and means responsive to the last impulse of the first series for releasing said switch and for electing a group of wipers.

23. In a telephone system, a selectively movable switch having a motor magnet, a stepping relay for closing the circuit of said magnet, a switching relay connected in series with said stepping relay, and means comprising a test wiper cooperating with test contacts in the bank of said switch for short circuiting said switching relay and for energizing said stepping relay if the said test contacts are busy.

24. In a telephone system, a selectively movable switch having a motor magnet, a stepping relay for closing the circuit of said magnet, a switching relay connected in series with said stepping relay, means comprising a test wiper co-operating with test contacts in the bank of said switch for short circuiting said switching relay and

for energizing said stepping relay if the said test contacts are busy, and contacts in the energizing circuit of said stepping relay controlled by said magnet, whereby the stepping relay and motor magnet constitute an interrupter mechanism for moving said test wiper over busy test contacts.

25. In a telephone system, a selectively movable switch having a motor magnet, a stepping relay for closing the circuit of said magnet, a switching relay connected in series with said stepping relay, means comprising a test wiper co-operating with test contacts in the bank of said switch for short circuiting said switching relay and for energizing said stepping relay if the said test contacts are busy, contacts in the energizing circuit of said stepping relay controlled by said magnet, whereby the stepping relay and motor magnet constitute an interrupter mechanism for moving said test wiper over busy test contacts, and contacts operated by said switching relay when said test wiper arrives at an idle contact for shifting the connection of said wiper to the other side of the switching relay.

26. In a telephone system, a selectively movable switch having a motor magnet, a stepping relay for closing the circuit of said magnet, a switching relay connected in series with said stepping relay, means comprising a test wiper cooperating with test contacts in the bank of said switch for short circuiting said switching relay and for energizing said stepping relay if the said test contacts are busy, contacts in the energizing circuit of said stepping relay controlled by said magnet, whereby the stepping relay and motor magnet constitute an interrupter mechanism for moving said test wiper over busy test contacts, contacts operated by said switching relay when said test wiper arrives at an idle contact for shifting the connection of said wiper to the other side of the switching relay, and means for completing the circuit of said relays over a new path including said wiper, said stepping relay remaining inoperative.

27. In a telephone system, a selectively movable switch, normally open talking circuit conductors in said switch, a switching relay for closing said conductors, a motor magnet and a stepping relay adapted to cooperate to effect selective movement of said switch, a test wiper and cooperating test contacts governing said selective movement, and suitable circuits for controlling said relays and said magnet, both of said relays being simultaneously connected to said wiper whereby when the said test contacts are busy the switching relay is prevented from energizing and the stepping relay is energized.

28. In a telephone system, a selectively

- movable switch comprising a motor magnet, a stepping relay therefor, a line switching relay, a test wiper and a bank of test contacts, means for completing a circuit through said relays, a branch of said circuit for short circuiting said switching relay and for energizing the stepping relay, means cooperating with said stepping relay for initially closing the circuit of said motor magnet, said magnet thereafter being under the sole control of the stepping relay, contacts in said first circuit and its branch opened by said magnet upon its energization, and alternative connections from said 10 relays to the test wiper whereby the continued short circuiting of the switching relay and the reenergization of the stepping relay is made dependent upon the presence of a test potential on the test contact with 15 which the test wiper has been moved into connection by the said energization of the motor magnet.
29. In a telephone system, a selectively movable switch having a motor magnet, means for operating said switch comprising a stepping relay for controlling said motor magnet, a line switching relay connected in series with said stepping relay, and means comprising a test wiper cooperating with 25 busy test contacts for short circuiting said switching relay and for energizing said stepping relay.
30. In a telephone system, a selectively movable switch having a motor magnet, means for operating said switch comprising a stepping relay for controlling said motor magnet, a line switching relay connected in series with said stepping relay, means comprising a test wiper cooperating with 35 busy test contacts for short circuiting said switching relay and for energizing said stepping relay, and contacts in the energizing circuit of said stepping relay under control of said motor magnet, whereby the said relay and magnet constitute an interrupter mechanism for causing step by step movement of said test wiper.
31. In a telephone system, the combination with an automatic switch having directive primary movement for selecting groups and automatic secondary movement for selecting an idle line in a selected group, of primary and secondary motor magnets in said switch, a stepping relay controlling said 40 secondary magnet, talking conductors, a switching relay controlling their continuity, means for connecting said relays in series during the secondary movement of said switch, a test wiper, and a connection from said test wiper to the junction of said relays.
32. In a telephone system, the combination with an automatic switch having directive primary movement for selecting groups and automatic secondary movement
- for selecting an idle line in a selected group, 65 of primary and secondary motor magnets in said switch, a stepping relay controlling said secondary magnet, talking conductors, a switching relay controlling their continuity, means cooperating with said stepping relay at the end of the primary movement of said switch for initiating the secondary movement, means for closing a circuit through said relays in series, and means comprising a test wiper cooperating with 70 busy test contacts for short circuiting said switching relay and for energizing said stepping relay.
33. In a telephone system, the combination in a selectively movable switch, of an operating mechanism comprising a cooperating stepping relay and motor magnet for driving the switch, a switching relay for closing the line circuit, means for closing a circuit for said switching relay in a preliminary movement of said switch, a test wiper and cooperating busy and idle test contacts, and circuit connections for preventing the energization of said switching 80 relay and for energizing said stepping relay while the said test wiper engages busy test contacts, said circuits including connections from said wiper to both of said relays.
34. In a telephone system, an automatic switch comprising passive contacts and a cooperating active contact, means outside said switch for rendering certain of said passive contacts busy, means for causing a preliminary movement of said switch to bring said active contact into association with said passive contacts, a control relay and a circuit therefor closed in said preliminary movement, a short circuit around said control relay to prevent its energization, a magnet and a cooperating stepping relay for advancing said active contact over said passive contacts, means operated each time said active contact comes into engagement with a passive contact for opening said short circuit, and circuit connections for maintaining a second short circuit independent of the first as long as said active contact engages busy passive contacts.
35. In a telephone system, a main exchange and a branch exchange, an automatic switch, having motion in two intersecting planes, trunk lines leading from said switch to each exchange, means for operating said switch in one plane in response to the first digit only of a called number to cause said switch to select trunks to the main exchange and for operating said switch in the same plane in response to the first and second digits of a called number to cause said switch to select a trunk to the branch exchange, said first digit in the second instance causing said switch to advance

and then release before the second digit is called.

36. In a telephone system, a main exchange and a branch exchange, an automatic switch, trunk lines leading from said switch to each exchange, a pair of wipers for said switch, means for operating said switch in response to the first digit only of a called number to cause said switch to connect with an idle trunk to the main exchange over one of said wipers, and for operating said switch in response to the first and second digits of a called number to cause said switch to connect with a trunk line leading to the branch exchange over the other of said wipers.

37. In a telephone system, a main exchange and a branch exchange, an automatic switch, trunk lines leading from said switch to each exchange, a pair of wipers for said switch, means for operating said switch in one instance in accordance to the first digit only of the called number to connect through one of said wipers to a trunk leading to the main exchange and for operating said switch in another instance in accordance with both the first and second digits of the called number to connect with a trunk line leading to said branch exchange, said first digit in the second instance causing said switch to advance and then release before the second digit is called.

38. In a telephone system, an automatic switch, trunk lines leading from said switch divided into main and subgroups, a pair of wipers for said switch for each main group of trunk lines, means for transmitting a single series of impulses to operate said switch to select a subgroup of one of said main groups over its associated wiper and for transmitting a plurality of series of impulses to said switch to cause the same to select a subgroup in another of said main groups through another pair of wipers.

39. In a telephone system, a combined first and second selector switch, a directive-ly operable primary magnet for controlling the operation of said switch, a plurality of pairs of wipers for said switch, means for operating said primary magnet in one instance by the impulses corresponding to the first digit only of a called number to extend a connection over one of said pairs of wipers, and for operating said primary magnet in another instance by the impulses corresponding to the first and second digits of the called number to extend a connection over another of said pairs of wipers.

40. In a telephone system, a plurality of exchanges, an automatic switch in one exchange, local trunk lines leading from said switch, other trunk lines leading from said switch to the other exchanges, a plurality of pairs of wipers for said switch, means

for operating said switch in accordance with the first digit only of a called number to extend a connection from said switch to one of said other trunk lines via one of said pairs of wipers and for operating said switch in accordance with the first and second digits of a called number to extend a connection from said switch to one of said local trunk lines via another pair of said wipers.

41. In a telephone system, a first selector having groups of wipers for use in connecting a calling and called line, means in said switch for changing from one group of said wipers to another group of said wipers and means for operating and releasing the same, both of said means responsive to the calling of the first digit in the number of the called line, means for reoperating said switch when the second digit is called, the second digit being the same as the first, and means for preventing the release of said switch when it is reoperated, the said switch being thereby enabled to extend the connection in the direction of the called line.

42. In a telephone system, a calling and a called line, a telephone number assigned to the called line, the first two digits in said number being the same, a first selector having groups of wipers operable in response to the calling of the first of said digits, means for automatically releasing said first selector the first time it is operated and for switching from one of said groups of wipers to another, means for preventing the release of said first selector when the second of said digits is called, the said first selector being operated to extend the connection in the direction of the called line, and other switches operable responsive to the remaining digits to complete the connection.

43. In a telephone system, means including a drop back selector for connecting calling and called lines, said selector having groups of wipers, groups of trunk lines accessible to said selector, calling dials at the stations on said lines, a shaft for operating all of the wipers of said selector responsive to a single operation of the dial at a calling station to connect with an idle trunk in one of said groups of trunks, and means requiring two successive and identical operations of the dial at said calling station to operate said selector to connect with an idle trunk in another of said groups.

44. In a telephone system, an automatic switch, two sets of wipers for said switch, said wiper sets being mechanically connected so as to always move together, a line incoming to said switch and normally associated with one of said wiper sets, means for connecting with said line for the purpose of operating said switch thereover,

restoring means for said switch, means responsive to the operation of said switch in a movement of definite and predetermined extent for shifting said line into association with the other of said wiper sets, and means also responsive to such primary movement for actuating said restoring means while maintaining the connection

to said line, whereby the said switch may be reoperated.

Signed by me at Chicago, Cook County, 10 Illinois, this 3rd day of November, 1915.

WINFRED T. POWELL.
